UNITED STATES PATENT OFFICE.

JAMES H. RAND, JR., OF NORTH TONAWANDA, NEW YORK.

CARD-INDEX SYSTEM.

1,142,728.

Specification of Letters Patent. Patented June 8, 1915.

Application filed June 17, 1914. Serial No. 945,731.

To all whom it may concern:

Be it known that I, JAMES H. RAND, Jr., a citizen of the United States, and resident of North Tonawanda, in the county of Niagara and State of New York, have invented new and useful Improvements in Card-Index Systems, of which the following is a specification.

This invention relates to card index systems, and consists in certain modifications 10 of a card system embodying the principles set forth in an application for Letters Patent of the United States filed by James H. Rand and James H. Rand, Jr., April 8, 15 1914, Serial No. 830,508.

In the accompanying drawings, which illustrate one embodiment of the invention, Figure 1 is a partial face view of a card system containing the invention; Fig. 2 is an 20 enlarged longitudinal section of said card system; Fig. 3 is a face view of one of the card-holders with its removable card, partly broken away; and Fig. 4 is a section on line 4-4 of Fig. 3.

25 A represents a sheet metal frame or panel, made with inwardly facing guide channels *a* to engage the ends of the bars on which the card-holders are mounted as hereinafter described.

30 The card-holders each consist of a sheet B of cardboard, or other suitable flexible sheet material, rigidly fastened at its lower edge to a bar C, by means of staples *c*, or other suitable fastening devices, so that when the 35 bar C is held in the frame as hereinafter described, the card-holder body will stand upright. The bar C is preferably made of some relatively stiff material such as heavy cardboard, possessing resiliency enough to 40 enable its ends to be sprung into the channels *a*, but stiffness enough to afford a firm support for the card-holders and cards.

The sheet B is made with slits *b* extending inward from the free or upper edge 45 toward the bar B, and dividing the sheet into a central or body section *b'* and two side sections or tongues *b*². The tongues may be of any desired height but are preferably a little shorter than the central or body 50 section, to facilitate the insertion of a card.

D represents a card which is preferably of the same width as the card-holder and of the same height as the body portion *b'*. The card is removably supported on the card- 55 holder by being inserted into the slits *b*, *b*, as illustrated, with the tongues and body

portion alternately overlying and underlying the card. The lower edges of the cards may be notched, as shown at *d*, to engage the ends of the slits *b*, *b* and hold the card against lateral displacement when mounted in the card-holder.

When the projecting ends of the bars C of a series of card-holders are inserted into the channels *a* of the frame, with the bars C one above another, the card-holders will be supported by their lower edges in upstanding position, with their upper edges free, so that the removable cards may each be inserted in or removed from their own proper card-holders without disturbing the others. And the card-holders and cards may be bent forward to admit of the inspection of underlying cards, and when released will fly back into upstanding position on account of their 75 resiliency.

The upper edge or margin of each card is exposed beyond the edge of the next overlying card, and as the cards and card-holders are coterminous at their upper edges, if 80 a card is removed, through accident or design, its absence is at once visually indicated both by the absence of its edge from the series of exposed card edges, and also more conspicuously by the exposure of the underlying card-holder, which may be provided with a signal, such as the words "Card cut," or a contrasting color of which the card-holder may be made, or any other appropriate signaling device. Such signal on the 85 underlying surface is normally concealed when the card is in position.

I claim:

1. A card system, comprising a series of upstanding card-holders supported at their lower edges and free at their upper edges, and a series of cards removably held by said card-holders, one in front of another with their upper edges exposed, whereby the absence of any card from its card-holder will 95 be visually indicated by the absence of its upper edge from the series of exposed upper card edges.

2. A card system, comprising a series of upstanding card-holders supported at their lower edges to overlap each other, and with their upper edges free and exposed, and a series of cards removably held by said card-holders, one in front of another with their upper edges exposed, each card-holder being 100 provided near its top with a signal normally concealed behind the exposed edge of its 110

- card, whereby the absence of any card from its card-holder will expose its underlying signal.
3. A card system comprising a series of upstanding card-holders, supported at their lower edges to overlap each other and with their upper edges free and exposed, and a series of cards removably held by said card-holders one in front of another with their upper edges exposed, whereby the absence of any card from its card-holder will be visually indicated by the absence of its upper edge from the series of exposed upper card edges.
- 15 4. A card system, comprising a frame having inwardly facing guide channels, and a series of card-holders each including means to support a removable card in upstanding position, said supporting means being provided with a pair of rigid, laterally extending projections, adjustably mounted in said guide channels, said projections being relatively broad and flat to prevent their turning in said guide channels, whereby said card supporting means and the cards held thereby will be rigidly supported in the frame by said projections in upstanding position.
- 20 5. A card system, comprising a frame having inwardly facing guide channels, and a series of card-holders each including means to support a removable card in upstanding position, a bar having relatively broad and flat ends projecting beyond each side of said card supporting means, to which bar said card supporting means is rigidly connected, said flat projecting ends of the bar being adjustably mounted in said guide channels and being adapted to prevent the bar from turning in said guide channels, whereby said card supporting means and the cards held thereby will be rigidly supported in the frame in upstanding position.
- 25 6. A card system, comprising a series of card-holders made of flexible sheet material, each formed with slits extending inward from one edge and dividing the card-holder into a central or body section and two end tongues, and a series of cards removably supported within said slits of the several card-holders, with said end tongues and body section alternately overlying and underly the cards, each card having notches in its edge to engage the ends of said slits.
- 30 7. A card system, comprising a series of card-holders made of flexible sheet material, each card-holder being provided with a bar at its lower edge on which the card-holder is rigidly supported, a series of cards removably held by said card-holders, and a frame having inwardly facing guide channels adapted to engage the ends of said bars and support said card-holders in upstanding position in the frame, one in front of another.
- 35 8. A card system, comprising a series of card-holders made of flexible sheet material and provided with card-engaging tongues, a bar at the lower edge of each card-holder on which the card-holder is rigidly supported, a series of cards removably held by said card-holders, the upper edges of the cards and of the body parts of the card-holders being substantially coterminous, and a frame having inwardly facing guide channels adapted to engage the ends of said bars and support them one above another, and to hold said card-holders in upstanding position in the frame one in front of another.
- 40 9. In a card system, a card-holder comprising a body made of flexible sheet material, and a relatively stiff bar to which said body is rigidly secured, said body being provided with slits extending inward from the free edge toward the bar, and a card removably supported in said slits.
- 45 10. In a card system, a card-holder comprising a body made of flexible sheet material, and a relatively stiff bar to which said body is rigidly secured, said body being provided with a pair of slits extending inward from the free edge toward the bar and dividing the card-holder into a central section and two side tongues, said central section being of greater height than said side tongues, and a card removably supported in said slits.
- 50 Signed by me at North Tonawanda, N.Y., this 9th day of June, 1914.
